Patented Oct. 9, 1917.

FIG. 1

FIG. 2

FIG. 4

INVENTOR
Philip D. Hibner

UNITED STATES PATENT OFFICE.

PHILIP D. HIBNER, OF SEATTLE, WASHINGTON.

ROTARY AIR-COMPRESSOR.

1,242,692.

Specification of Letters Patent. Patented Oct. 9, 1917.

Application filed July 1, 1916. Serial No. 107,053.

To all whom it may concern:

Be it known that I, PHILIP D. HIBNER, a citizen of the United States, residing at Seattle, in the county of King and State of Washington, have invented certain new and useful Improvements in Rotary Air-Compressors, of which the following is a specification.

This invention relates to rotary air-compressors, although it may be usefully employed in pumps, etc.

The object of my improvements is to provide a simple and inexpensively constructed machine of this type which will perform a relatively high amount of work with a minimum consumption of power, which will operate with little vibration and wear, and deliver a fluid from the compressor at a uniformly high pressure.

The invention consists in the novel construction, adaptation and combination of parts, as will be hereinafter described and claimed.

In the accompanying drawings, Figure 1 is a transverse vertical section of a fluid compressor embodying my invention. Fig. 2 is a horizontal section taken substantially through 2—2 of Fig. 1. Fig. 3 is a fragmentary sectional view similar to Fig. 1 with the rotor and a slide shown in different relative positions from which they are represented in Fig. 1. Fig. 4 is a detail sectional view taken substantially through 4—4 of Fig. 1.

Referring to the drawings, the numeral 5 designates the machine casing or cylinder. Extending concentrically through the bore thereof is a power-driven shaft 6 upon which is rigidly mounted a rotor 7. This rotor is of a substantially elliptical form in transverse section and of a size to have its major axis equal to the internal diameter of the cylinder, or nearly so, when packing strips 8 are utilized to fit against the peripheral surface of the cylinder bore.

The cylinder is provided at diametrically opposite sides with chambers 9 to accommodate radially disposed plates or slides 10. Said chambers have communication through 50 passages 11 with the branches 12 of a discharge pipe 13.

Provided in each of said passages is a seat 14 for an outwardly opening valve 15 which is yieldingly held in its closed position by 55 means of a spring 16 interposed between the

respective valve and a washer 17 whereby the tension of the respective spring is regulated through the agency of an adjusting screw 18.

At diametrically opposite sides of the cylinder and in proximity of the respective slides 10, are series of air-inlet openings 19 separated by diagonally arranged partitions 20, shown in Fig. 4. At the intake end of each of the series of openings 19 is a strainer 65 of wire gauze or an equivalent.

The slides 10 are advantageously provided upon their inner ends with suitable packing or wearing strips 22 which are held against the rotor by the slides being pushed 70 inwardly of the cylinder by means of springs 23 whose effective power may be regulated by adjusting screws 24.

Each of the slides is provided in its side remote from the adjacent inlet openings 19 75 with a recess 25 which extends from the inner end of a slide to a distance therefrom sufficient to reach the associated passage 11 when the rotor is in approximately the position in which it is illustrated in Fig. 1. 80

The operation of the invention is as follows:

The rotor is driven in the direction indicated by arrows α in Figs. 1 and 3, and as each of the extremities of the rotor revolve 85 past the inlet openings 19, the fluid to be compressed is drawn into the cylinder to follow the rotor while the fluid supplied to the cylinder in the preceding cycle of operation is compressed in advance of the major 90 axis and the respective slides 10.

By reason, however, of the recesses of the slides being in operative positions during the early portions of the inward movements of the slides, the springs 16 and such fluid 95 pressure as obtains to the rear of the valves will prevent any of the fluid escaping from the cylinder into said discharge pipe until such pressure is sufficient to overcome the referred to opposing pressure plus that exerted by the springs.

When such fluid pressure is generated in the cylinder, it will not be capable of escaping into the discharge pipe until, during the ultimate portions of the successive 105 cycles, the slide recesses 25 afford conduits for the compressed fluid to passages 11. Thus it will be seen that the fluid is compressed to a relatively high pressure within the cylinder, and the check valves 15 work 110

periodically and serve to minimize the amount of return flow of compressed air into the cylinder.

What I claim as my invention is—

- 5 1. In apparatus of the class described, a cylinder provided with inlet and outlet openings, spring-pressed non-return valves provided for said outlet openings, a power-driven shaft extending concentrically through the cylinder bore, an elliptic rotor mounted on said shaft, packing strips provided for the rotor, and radially disposed slides arranged for reciprocatory movement in the cylinder, springs tending to maintain said slides in contact with the periphery of the rotor, said slides being provided with recesses whereby they serve as valves to regulate the delivery of fluid compressed in the cylinder.
- 10 2. In a compressor, a cylinder provided with an inlet opening, and an outlet opening, a rotor, means to rotate said rotor, a reciprocatory member serving as an abutment for the rotor and also as a valve with respect to said outlet opening, and means cooperating with said member whereby fluid compressed within the cylinder can be discharged through said outlet during only the latter part of each cycle of said rotor's operation.
- 15 3. In apparatus of the class described, a cylinder provided in its circumferential wall

with a discharge passage, a rotor rotatable within the cylinder, a valve positioned in said outlet close to the inlet end of said discharge passage, and a slide coöperating with the rotor to afford pressure within the cylinder and periodically interrupt communication between the interior of the cylinder and said valve.

35 4. In apparatus of the class described, a casing provided with a cylindrical bore and having fluid inlet and discharge openings at opposite sides thereof, a substantially elliptical rotor mounted within said bore, a slide provided with a recess and serving as an abutment with respect to said rotor, a spring coöperating with said rotor to effect reciprocatory movements of the slide whereby the recess thereof is moved into positions to alternately render said discharge opening operative and inoperative, and a spring-pressed valve positioned to close said discharge opening until the spring thereof is overpowered by fluid pressure obtaining 40 within the casing during the periods when said slide is in position to afford an outlet through the recess thereof.

45 Signed at Seattle, Washington, this 26th day of June, 1916.

PHILIP D. HIBNER.
